UNITED STATES PATENT OFFICE

2,500,003

SKIMMER GOLF GAME

Edward J. Miller, Lansdowne, Pa.

Application November 25, 1946, Serial No. 712,073

1 Claim. (Cl. 273—33)

1

My invention relates to a game of skill somewhat on the order of golf, but using thin flat disks, shells or other buoyant missiles instead of golf balls, the disks being sent off by a blow from an ordinary golf stick to skim over the water, the number of touches of the disk as it skims the top of the water making up the score.

Instead of an ordinary tee, a slanting delivery board for carrying the disk is provided and from which the disk is sent off.

In the drawing one embodiment and some modifications of my invention have been illustrated.

Figure 1 is a top plan view of an inclined delivery board from which the disk is sent off;

Figure 2 a section in a vertical plane along line 2—2 of Figure 1;

Figure 3 is a modification showing a side view of a horizontal delivery board with a tee in the form of an upstanding coiled spring for carrying the flat disk;

Figures 4 and 5 show in top plan elevation and side view respectively, a delivery board similar to the construction shown in Figure 1 and Figure 2, with a swiveled block for supporting the disk.

In the drawing like numerals relate to the same details in the different views.

Referring first to Figures 1 and 2, numeral 10 shows the base or flat board which, in the use of the invention, is placed directly on the ground at the shore of a lake or beach of the sea. Upon this base 10 is hinged, as at 11, a delivery board 12, slanting upwardly about 15 to 30 degrees, adjustable by a coiled spring 13 inserted between the two boards in a long slit 14 on the base 10 by screw stud 15. In order to set up friction with the ground and prevent slipping, the base 10 may be provided with a number of pegs 16.

In playing the game, the device is set up near the water with the open jaw of the delivery board facing the water. A round or oblong flat disk 17 is thereupon placed near the edge of the delivery board 12 and by using a golf club 18 or similar implement to deliver a blow against the rear edge of the disk, the disk is sent skimming over the water. The disk will then take several jumps or follow a wavy path over the water, until it finally settles down thereon. The number of skips and jumps from contact with the water are then counted, to make up the score. The game is usually played with ten disks for each player and the total number of such contacts added together for each player determining which one is the winner.

Instead of flat round disks, the game may be

2

played with oblong missiles, clam shells, flat stones or the like.

The device shown in Figure 3 is a slight simplification of the one described. The same has the same kind of base 10 on feet or pegs 16 with spring 13 and screw stud 15, but no delivery board. The disk 17 is instead placed directly on top of the coiled spring 13 from which it is sent off by a blow from the golf stick 18. The supporting spring 13 will then vibrate back and forth but gradually regain its upright position for the next shot.

In Figures 4 and 5, still another modification is shown although the base 10, delivery board 12, spring 13, hinge 11 and pegs 16 are the same. The difference consists in the provision of a weighted tumbler or block 20 hung on a pivot pin 21 so as to remain in upright position even when the disk 17 is placed on top thereof. The tumbler or block hangs freely in a rectangular opening 22 provided in board 12, so that it may describe a complete somersault, when the blow is delivered, and then immediately returned to upright position, ready for the next shot.

It is to be understood that the invention as herein disclosed may be varied from the details described and shown without departure from the spirit of the subjoined claim.

It is pointed out that the spring 13, in order to regulate the angular inclination of the board 12, is attached to said board by a bolt or screw stud 15, in an oblong hole or slit 14, in the middle of the board. By this means, the regulating spring 13 may be shifted back and forth on said board to give the desired inclination of 15 or more degrees of the board. This variable inclination being necessary to change delivery for different tides or according to the players own requirement. Depending on the manner he delivers a strike, causing vibration of the board, governs the number of contacts of the missile with the water.

I claim:

A game device of the character stated designed to be played with an aerial missile, comprising a relatively long, wide and flat base designed to be disposed for use flat upon the ground, a relatively long missile supporting board disposed upon the base and hingedly secured across one end to the base, said board being of materially less length than the base and disposed with the end edge remote from the secured end substantially flush with an end edge of the base, the base being provided with a longitudinally extending slot beneath said board at approximately midway be-

tween its ends, an upstanding stud extending through said slot and adapted for movement longitudinally thereof but held against withdrawal upwardly through the slot, the slot length being in the direction of the length of the board, and a coil spring resting upon the base over the slot and connected with said stud, the upper end of the spring having the board resting thereon, the spring being adjustable with the stud lengthwise of the board whereby to support the board at different degrees of inclination.

EDWARD J. MILLER.
